UNITED STATES PATENT OFFICE.

WILLIAM F. MORRISON, OF VALLEJO, CALIFORNIA.

CONCRETE RAILROAD TIE.

1,410,496.

Specification of Letters Patent. Patented Mar. 21, 1922.

Application filed November 23, 1921. Serial No. 517,209.

To all whom it may concern:

Be it known that I, WILLIAM F. MORRISON, a citizen of the United States, residing at Vallejo, in the county of Solano and State of California, have invented new and useful Improvements in Concrete Railroad Ties, of which the following is a specification.

The present invention relates to improvements in concrete railroad ties and the primary object of the invention is to provide a concrete tie which will have maximum resiliency, be strong and durable and of such a structure and arrangement that should breakage occur such breakage will take place at such points in the tie as to leave equal portions of the tie intact on opposite sides of points where the rails are supported, the said tie being formed so as to be relatively weak at equa-distantly spaced points from opposite ends so that, for example, in a tie of a length of 8 feet, the weak points would be formed at points approximately 3 feet from each end.

An object of the invention is to provide a tie of the character described which may be simply, easily and inexpensively made and which, owing to the provision of the weak points hereinbefore described, will be more resilient than otherwise.

Another object of the invention is to provide a tie of the character described which will positively hold the rails against spreading, due to the employment of simple, inexpensive, strong rail clamping means and reinforcing means of the tie proper, which latter provides durability, strength and resiliency.

Another object is to provide in a tie of the character described a rail clamping means which is small, compact, consists of few parts, is capable of being readily and easily assembled and disassembled and which when worn on one side may be reversed to present a new clamping and engaging portion.

The invention possesses other advantages and features some of which, with the foregoing will be set forth at length in the following description where I shall outline in full that form of the invention which I have selected for illustration in the drawings accompanying and forming a part of the present specification. In said drawings I have shown one form of the construction of my invention, but it is to be understood that I

do not limit myself to such form since the invention as expressed in the claims may be embodied in a plurality of forms.

Referring to the drawings;

Fig. 1 is a top plan view of the tie of my invention.

Fig. 2 is a side elevation of the tie.

Fig. 3 is a fragmentary longitudinal sectional view of the tie.

Fig. 4 is a cross sectional view through the mold such as used for forming the tie, showing the means for and manner of forming the weak points in the tie body.

Fig. 5 is a perspective view of one of the rail clamps as used upon the innerside of the rail.

Fig. 6 is an elevation taken on line 6—6 of Fig. 5.

Fig. 7 is a perspective view of the type of rail clamp used upon the outer side of the rails.

Fig. 8 is a sectional view taken on line 8—8 of Fig. 7.

Fig. 9 is a cross sectional view through the tie of this invention showing the rail clamping means as when clamping the rail upon the tie.

Fig. 10 is a side elevation of one of the bolts used in connection with the rail clamping means.

Fig. 11 is a detail of a portion of one of the supporting plates.

Referring to the present embodiment of the invention as illustrated in the accompanying drawings, 1 designates a concrete tie of substantially standard dimensions, which tie is reinforced by two sets 2 and 3, of longitudinal reinforcing rods. The set 2 extends uppermost in the tie longitudinally thereof with straight upper portions 4 and bowed or V shaped end portions 5, the bowed end portions being of a downward bow disposed beneath said portions 4 and forming, as it were, with said portions 4, triangular frames at the ends of the tie. The rods of the set 3 extend straight through the lower part of the tie below the portions 4.

The tie of this invention is constructed so that it will have points of weakness at points equally spaced from the ends of the tie, whereby when severe shocks, strains and stresses are taken up by and cause the tie to break, the breaks will occur at said points of weakness, which points are arranged so that the remaining or broken portions of

the tie will be sufficient in length to provide adequate supporting members for the rails.

In carrying out this arrangement in a tie say, of the length of 8 feet, at points 3 feet from each end of the tie, there will be formed around the outer and upper sides of the tie only, a cut, crack or recess 8 which will extend into the tie say, for an inch and three quarters and be substantially one thirty-second of an inch in width. To provide for this arrangement, in the forming of the tie, one practical way of forming the weak points is shown in Fig. 4 and consists in using inverted substantially U shaped mold pieces 9 which are adapted to engage in grooves 10 formed in opposite walls of the mold 11. These pieces are an inch and one-half wide and substantially one thirty-second of an inch thick, and are fitted in place around the reinforcing rods, as shown in Fig. 4. When the concrete is poured into the tie, it will form around the members 9 and the groove 8 will be provided in the opposite sides at the top of the tie at points three feet from each end of the tie. To further render the central portion of the tie relatively weak, this portion is reduced slightly as to transverse thickness, the reduction taking place from the points 12, which points will be 6 inches outwardly spaced from the grooves 8. The remaining portions of the tie will have downwardly and outwardly inclined sides and preferably be wider at the bottoms than at the tops thereof. Preferably the dimensions of these portions being widths of 8 inches along the tops, 9 inches along the bottoms with the height of the sides being preferably 9 inches. It will thus be seen that the rail supporting portions of the tie, that is the portions at and on opposite sides of the points where the rails are supported, are of relatively heavier construction and of greater strength than the mid portion of the tie.

I have found that in the ordinary concrete tie, the tendency is for the tie to break at points between and close to the rails. This is largely due to the fact that concrete ties are not sufficiently resilient to withstand the shocks, jars and strains occurring incident to the usage to which the ties are usually subjected. Therefore, by provision of the grooves 8 which render the tie relatively weak and by the forming of the central portion of the tie of less thickness than the remaining portion, the tie is strained so as to break at the weak points or grooves 8 and will thus provide longer and more heavily constructed portions of equal and adequate size to properly support the rails. Thus all possibility and danger of the tie breaking close to the rails is eliminated. For example, in a tie of 8 feet, if the tie is strained to break at two intermediate points, 60 two feet apart and each point three feet from

an end of the tie, there will remain a three foot section or portion of the tie for supporting each rail, the rails on these sections being supported centrally of the ends of said sections. I have found that by forming the grooves or weak points at the sides and top only, of the tie and by use of the reinforcing rods, the tie is sufficiently strong to withstand ordinary strains and stresses without breaking and has a great deal more resiliency than when otherwise constructed. However, when breaking strains and stresses are transmitted to the tie, by reason of these grooves the breaks will occur evenly at the grooves and by so controlling the breaking points the efficiency of the tie is not, if at all, greatly impaired even after the breaking thereof.

Embedded in the tie adjacent the ends thereof are bolts 14 having enlarged heads 15 anchored in the concrete. These bolts extend above the upper surface of the tie so as to provide for attachment of the rail clamping devices thereto and are screw threaded as at 16 at their upper ends. Formed transversely in the upper surface of the tie are recesses 17 in which are mounted wooden cushion blocks 18, the upper sides and ends of which terminate substantially flush with the upper faces and sides of the tie. The bolts 14 extend through openings 19 in the cushion blocks and are provided with shoulders 20 intermediate of their ends, which shoulders engage the under faces of said blocks. Metal supporting plates 21 are mounted upon the blocks 18 and have depending flanges 22 on opposite ends, which flanges engage opposite edges of the blocks and extend below said blocks so as to overlie the tie proper, as shown in Fig. 9. The rail supporting plates 21 have openings 23 therein through which the bolts 14 extend. Mounted to engage the flanges 24 of the rails 25 upon the inner sides of the rails, are rails clamping blocks 26 having central openings 27 through which certain of the bolts extend. Nuts 28 are turned upon the bolts and screwed down to engage the clamping blocks 26 so as to hold one of the bevelled ends 29 of the block in engagement with the rail flanges. The bevelled ends 29 are formed so as to provide shoulders 30 to engage the outer edges of the rail flange. The ends of the block are formed alike and provided with the bevelled faces on opposite sides so that when the clamps become worn at one end they may be reversed to present new clamping faces.

A different type of rail clamping block is used to engage the flanges on the outer sides of the rails. A block of this type is shown in Figs. 7 and 8, and comprises a rectangular body portion 31 having the upper and lower sides thereof at its ends oppositely bevelled as at 32 and 33, and being provided with

shoulders 34 corresponding to the shoulders 30. Extending from opposite sides of the body portion are lugs or projections 36 and 37 adapted to snugly engage in openings 38 formed in the metal plates so as to prevent slipping of the clamps on said plates. An opening 40 extends through the lugs and body portion and receives the other bolts 14. Nuts 42 are turned upon the screw threaded 10 ends 16 of the bolts and screwed down to engage one of the lugs on the body portion. When one bevelled face of the clamp becomes worn the clamp may be inverted to present the other bevelled face for engagement with the rail flange. One of the other 15 of the lugs or projections 36 and 37 at all times engages in the openings in the metal plate 21, at each end of the tie. The faces of the clamps opposite the bevels are flat as 20 at 43 and rest upon the plates 21.

I claim:

1. A concrete railroad tie being constructed with a relatively weak mid portion and having breaking points formed by the formation of cracks or recesses extending into the body of the tie at points so spaced from the ends thereof that should breaking strains and stresses be submitted to the tie, breaking thereof will take place at points 25 spaced inwardly from those portions of the tie over which the rails are supported.

2. A concrete railroad tie being constructed with a relatively weak mid portion and having breaking points formed by the formation of cracks or recesses extending into the body of the tie at points so spaced from the ends thereof that should breaking 30 strains and stresses be submitted to the tie,

breaking thereof will take place at points spaced inwardly from those portions of the tie over which the rails are supported and reinforcing elements extending longitudinally in the tie.

3. A concrete railroad tie made up of a mono-lithic structure and having breaking points provided by the formation of cracks or recesses extending into the body of the tie at points spaced from the ends thereof whereby, when breaking strains or stresses are submitted to the tie, the tie will break at said weak points.

4. The method of forming a concrete railroad tie with cracks or recesses extending into the body of the tie at points spaced inwardly from the ends thereof and from those portions of the tie over which the rails are supported, which consists in molding a complete tie in a mold structure adapted to form inwardly extending cracks or recesses in a monolithic structure, allowing the concrete to set and then removing the same from the mold or vice versa.

5. The method of forming a concrete railroad tie with cracks or recesses extending into the body of the tie at points spaced inwardly from the ends thereof and from those portions of the tie over which the rails are supported, which consists in pouring concrete into a mold containing reinforcing elements adapted to be embedded into the tie and mold means adapted to mold or form recesses extending into the body of the tie, allowing the concrete to harden and then removing the concrete from the mold.

WILLIAM F. MORRISON.
